UNITED STATES PATENT OFFICE

105,440

DESIGN FOR A DRESS

Joseph Rosenberg, New York, N. Y.

Application June 9, 1937, Serial No. 69,748

Term of patent 3½ years

To all whom it may concern:

Be it known that I, Joseph Rosenberg, a citizen of the United States of America, residing in Manhattan, county of New York and State of New York, have invented a new, original, and ornamental Design for a Dress, of which the following is a specification, reference being had to the accompanying drawing, forming part thereof, wherein,

The clustered floral groupings relatively arranged on the dress, as shown, represent raised corded embroidery.

The bow on the front bodice portion of the dress has a jeweled ornamentation thereon.

I claim:

The ornamental design for a dress, substantially as shown, and described.

JOSEPH ROSENBERG.
